(57) **CLAIM**

The ornamental design for a computer mouse as shown and described.

DESCRIPTION

1. Computer mouse
  - 1.1: Perspective
  - 1.2: Front
  - 1.3: Back
  - 1.4: Left
  - 1.5: Right
  - 1.6: Top
  - 1.7: Bottom
1. The application of the present appearance design: used to connect to a computer as an input device to control the computer; 2. The key point of the present appearance design: partial protection of the product's shape; 3. Images or photographs that best represent the key design features: perspective view; 4. The broken lines in the drawings illustrate portions of the computer mouse that form no part of the claimed design.
